UNITED STATES PATENT OFFICE.

AUGUSTUS H. JONES, OF MERIDEN, CONNECTICUT, ASSIGNOR TO THE A. H. JONES CO. INC., OF MERIDEN, CONNECTICUT, A CORPORATION OF CONNECTICUT.

DESIGN FOR A CASKET-LIGHT FIXTURE.

Application filed September 16, 1926. Serial No. 19,089. Term of patent 7 years.

To all whom it may concern:

Be it known that I, AUGUSTUS H. JONES, a citizen of the United States, residing at Meriden, in the county of New Haven and State of Connecticut, have invented a new, original, and ornamental Design for a Casket-Light Fixture, of which the following is a specification, reference being had to the accompanying drawing, forming part thereof.

Fig. 1 is a face view of a casket light fix-ture showing my new design and representing three clusters of flowers, each of which masks an electric light bulb indicated by broken lines;

Fig. 2 is an end view of the same on a smaller scale.

I claim:

The ornamental design for a casket light fixture as shown.

A. H. JONES.
